UNITED STATES PATENT OFFICE.

JAMES A. ELPHINSTONE, OF PITTSBURG, PENNSYLVANIA.

RETAINING DEVICE FOR LACES.

No. 888,978.

Specification of Letters Patent.

Patented May 26, 1908.

Application filed October 23, 1907. Serial No. 398,731.

To all whom it may concern:

Be it known that I, JAMES A. ELPHINSTONE, a citizen of the United States, residing at Pittsburg, in the county of Allegheny and State of Pennsylvania, have invented certain new and useful Improvements in Retaining Devices for Laces, of which the following is a specification, reference being had therein to the accompanying drawing.

10 My invention refers to an improved device for holding the loose ends of tie strings, and is particularly designed for use on laced shoes, although the invention may be used with gloves, corsets, etc., with good results.

15 Ordinarily, when the laces of shoes are tied in a knot, the looped and loose ends are either left loosely depending from the top of the shoe, or tucked into the top of the shoe, but either arrangement is unsatisfactory in 20 that the lace ends especially are very long and are not retained in place and dangle down, becoming untied or soiled or loosening the knot.

25 The invention consists of a retaining spring hook adapted for attachment to the shoe top at one side, and so constructed that it will effectually hold the lace in position, due to the peculiar construction of the spring arm and back.

30 Referring to the drawings:—Figure 1 is a perspective view showing the device in use. Fig. 2 is a plan view, enlarged. Fig. 3 is a cross sectional view on the line III. III. of Fig. 2.

35 The device consists of a spring hook having a securing base 2 adapted for attachment by rivets or otherwise, with a forwardly extending back portion 3, forming one side of the retainer proper.

40 4 is the outer or front spring hook, curved outwardly at its tip 5 for clearance and ease of entrance of the lace ends, the spring hook being joined with back portion 3 by a half round bend 6.

45 As thus made an enlarged interior cavity is provided at the inner portion of the space between back 3 and front 4, which ordinarily would be too large to have any gripping effect on the lace ends, and for the purpose 50 of reducing the space and for providing interior gripping elements for the lace, each of said elements is corrugated or provided with irregular co-acting faces. Thus the back is provided with one or more outwardly bulging ribs 7 while the front 4 is similarly provided

with corresponding inwardly bulging ribs 8, the several ribs of each part with their intervening or flanking recesses being so arranged with relation to each other that they will alternate in position. That is to say, the rib 60 7 of back 3 projects into the recess between inwardly extending ribs 8, while said ribs 8 in turn extend towards the recesses at each side of rib 7, or the respective reaction of the faces of the back and front may be reversed, 65 if desired. By this arrangement it will be seen that when the lace ends are inserted between the back and front members they will be forced between the ribs and recesses, occupying a sinuous position from top to bottom. It will be understood that the intervening space is such that when the lace ends are inserted the pressure will bind them tightly, gripping the ends by the ribs and recesses, and securely holding them against 70 accidental release.

The ribs as shown extend along the body portion of back 3 and front 4 sufficiently far to embrace and hold the several ends, the inner portion of end 5 being rounded closely 80 toward the face of the base and practically closing the opening to insure the retention of the lace ends.

The device is very simple and effective. It may be made with different designs of 85 gripping faces to cause holding action on the laces, and in different forms or arrangements, or otherwise changed by the skilled mechanic within the scope of the invention.

What I claim is:—

90 A lace holder consisting of an attaching base bent upon itself to provide an outer resilient arm and an intervening transverse space and deflected inwardly to form a curved outwardly turned terminal closely 95 adjacent to the base, said base being provided at its rear portion behind such terminal with an outwardly extending rounded projection longitudinal of its middle, the outer portion of the device having a similar outwardly rounded middle projection opposite said portion, substantially as and for the purpose set forth.

In testimony whereof I affix my signature in presence of two witnesses.

JAMES A. ELPHINSTONE.
